QUICK ATTACHABLE AND DETACHABLE
SHOESHINE STAND FOR BARBER
CHAIRS

John Weber, Oakland, Calif.

Application April 16, 1948, Serial No. 21,513

6 Claims.

(Cl. 15—265)

1

This invention relates to improvements in shoe shine stands and particularly those which are attachable to a barber chair to permit shining of a person's shoes while he is simultaneously obtaining tonsorial services.

The conventional shoe shine attachment is capable of being attached to only one type of chair, or chairs of one specific width between legs, therefore a different type must be provided for each different type of chair. In addition, the foot rests are non-adjustable, so that depending on the adjustment of the chair, the person may find more or less discomfort in the position of his feet during the shoe shining process. Furthermore, the chair cannot be raised as the shoe shine stand must be supported in a definite position on the floor.

This invention overcomes all of these disadvantages because of practically universal adjustments. The foot rests are adjustable for comfort, the stand is adjustable to fit any chair, and the chair can be raised or lowered to its limits of vertical adjustments without raising or lowering the stand; and a special adjustment prop is provided to support the front portion of the stand when the chair is tilted when it is in an elevated position. The stand is quickly attachable to and detachable from the chair and retains its relative position irrespective of vertical adjustments of the chair.

The objects and advantages of the invention are as follows:

First, to provide a shoe shine stand which is adjustable to fit any barber chair.

Second, to provide a stand as outlined which is releasably attachable to the barber chair and will maintain its relative position irrespective of vertical adjustments of the chair.

Third, to provide an attachment as outlined with a front prop which is adjustable to support the front of the stand for any inclined adjustment of the chair when the chair is in an elevated position.

Fourth, to provide a stand as outlined with foot rests which are quickly manually adjustable relative to the chair to provide the greatest degree of comfort for the person having his shoes shined.

In describing the invention reference will be had to the accompanying drawings in which:

Fig. 1 is a perspective view of the invention.

Fig. 2 is an enlarged fragmentary view partly in section of the end portion of the foot rest clamp, looking in the direction of the arrow on Fig. 1.

Fig. 3 is a rear view of one of the latching devices for latching the shoe shine stand to a barber's chair.

Fig. 4 is a longitudinal section through the support bar and foot rest base with the base in locking position.

The shoe shine stand includes two side panels 10 and 11 secured in spaced relation by bars 12, 13 and 14 each of which is slotted at its opposite ends as indicated at 16, 17 and 18 and secured by screws 19 and 20 in any adjusted position. Also spanning the space between the side panels is a tie rod 21 which is threaded at each end as indicated at 22 with nuts 23 and 24 clamping the panels and providing a rigid structure.

10 The bar 13 has an integral partitioned box 25 to hold shoe shine materials, and a base 26 spans the space between the side panels when the panels are adjusted to their closest position, this base being supported between the back and front tie bars 14 and 12, and terminating at 27 and 28.

15 The front prop 29 is slotted throughout the major portion of its length as indicated at 30 for sliding reception of the screw 31 which is anchored in the cross-member 14, the prop being turned to an upright position as indicated at 29' and clamped in adjusted position by the thumb nut 32 to support the front end of the stand when the chair is tilted from an elevated position.

20 Mounted on the backs of the respective side panels are latching members, respectively 33 and 34 which are provided with arcuate slots 35 through which they are slidably held by screws 30 35' entering the lugs 36.

25 Angles 37 form shoulders for carrying the weight of the stand, and mounted on top of each of these angles is a bar 38 terminating at the rearward end in a lug or stop 39. Mounted on each of these bars is a shoe 40 which is channel shaped to freely rest on the bar 38, and having a lug 41 projecting inwardly from the lower portion of the channel leg on each side, and with the web 42 of the channel cut out at the rearward 30 end as indicated at 43 to provide a passage at 44 for the bar, the rearward end of the lug being brought to an edge as indicated at 45. Mounted on each shoe is a foot rest 46.

35 To adjust the stand, the latching members 33 and 34 are pressed outwardly (33 to the right viewing Fig. 3), the nuts 23 and 24 and all screws 19 and 20 are loosened, the side panels are adjusted against the bracket arms 49 of the chair foot rest, and the nuts adjusted and tightened, 40 after which the cross bars 12, 13 and 14 are moved to an intermediate degree of adjustment and the screws tightened. The latches 33 and 34 are now pressed toward each other causing the latches to first rise then drop as the arcuate slots 45 pass over the screws and terminating with the screws in the high ends of the slots on one side, and locking the stand to the chair foot rest. Thus, with these arcuate slots the latches are 50 retained in either locking or freeing position, and

a slight blow on one side of the latch will move and latch the latch in the other position.

The stand is placed to span the foot rest brackets of the chair with the engaging members 33 and 34 drawn outwardly, and when struck or forced from the outside they will move in as indicated at 34 to engage the foot rest brackets and latch in that position. As the chair is elevated, the foot rest brackets slide up in the space between the latch and the flange 51. Tilting the chair causes the bracket to raise still higher, thus engaging the top flange 31 and raising the stand. The prop is then adjusted as desired, to either keep the stand level or tilted. The foot rests are adjusted by raising the front end of the shoe and sliding to the desired position, then releasing. The stop lug 39 is provided to engage the rear ends of the lugs 41 to prevent movement or adjustment of the shoe off of the bar 38 accidentally, limiting such movement or adjustment to the rearward end of the bar. The weight of the shoe and foot rest will in itself lock the shoe in position because of the grip on the bar between the edges 45 and 47. When the chair is adjusted vertically the attachment will maintain its position, while if the chair is adjusted vertically and tilted, the bracket arms 49 will engage the top member 37 and raise the stand. The leg 29 is released through operation of the thumb nut 32, swung to a vertical position as indicated by the dotted figure at 29' and allowed to rest on the floor with the stand adjusted as desired to a level or tilted position, and the thumb nut again tightened. Suitable casters 48 are provided for convenience in moving the stand from one chair to another. Obviously all chairs in a barber shop are of the same type so that these stands need only be adjusted for that specific type of chair, and if in any case there should be several types of chairs, several different stands can be individually adjusted to suit.

I claim:

1. A shoe shine stand for releasable attachment to a barber chair having spaced foot-rest bracket arms, comprising a pair of side panels and a plurality of cross members with the side panels and cross members relatively adjustable to adjust the span between the side members, and including latching means on said side panels for releasably securing the stand to the chair; said cross members including a front cross member and a prop foldable along said cross member when not required and adjustable at right angles and vertically on said cross-member as to height at will to support the front end of said attachment when the chair is adjusted to a reclined and raised position, and a support member located on the inside face of each side member for support of the rearward end of the stand by said bracket arms when the chair is elevated and tilted.

2. A shoe-shine stand comprising; a plurality of cross members; a pair of side panels spaced adjustable and securable in adjusted position on said cross members; a vertical guideway on the inside of each side panel to receive the respective foot-rest bracket arms of a barber chair and said vertical guideway including latching means on said side panels for releasably securing the stand to said bracket arms.

3. A structure as defined in claim 2; an adjustable foot rest mounted on the top of each

side panel and adjustable therealong and including means for releasably securing the foot rest in adjusted position.

4. A structure as defined in claim 2; said vertical guideway including a stop and support member located at the upper end of each panel for support of the rearward portion of said stand by said bracket arms when the chair is elevated and reclined, and one of said cross members comprising a front cross member having a prop vertically adjustable thereon for support of the front portion of the stand when the rearward portion is supported by the bracket arms for support in horizontal or tilted position as desired.

5. A structure as defined in claim 2; an adjustable foot rest mounted on the top of each side panel and adjustable therealong and including means for releasably securing the foot rest in adjusted position; said vertical guideway including a stop and support member located at the upper end of each panel for support of the rearward portion of said stand by said bracket arms when the chair is elevated and reclined, and one of said cross members comprising a front cross member having a prop vertically adjustable thereon for support of the front portion of the stand when the rearward portion is supported by the bracket arms for support in horizontal or tilted position as desired.

6. A shoe-shine stand comprising; a pair of spaced side panels, a plurality of spacer members including a front member for said side panels, with said side panels spacedly adjustable thereon; a foot rest adjustably mounted on the top of each side panel for adjustment in a direction normal to the top of the side panel; a prop foldable parallel to and movable to a right angular position and vertically adjustable and securable on said front member for support of the front end of said stand in an elevated position; a guideway extending throughout the major portion of the height and extending to the top of each panel and located on the inside surface of the panel and including a flat bar laterally movable to two positions and mounted on the rear edge of the panel, to lock the stand to the foot-rest bracket arm of a barber chair when in one position and to release the stand for removal when in the other position, and a support member located at the upper end of the slide way for support of the rearward end of the stand by said bracket arm when the chair is elevated and tilted.

JOHN WEBER.
